UNITED STATES PATENT OFFICE.

HEINRICH DEGENER, OF BERLIN, GERMANY, ASSIGNOR TO MERGENTHALER LINOTYPE COMPANY, A CORPORATION OF NEW YORK.

LINE SETTING AND CASTING MACHINE.

1,075,024.

Specification of Letters Patent.

Patented Oct. 7, 1913.

Application filed September 12, 1910. Serial No. 581,533.

To all whom it may concern:

Be it known that I, HEINRICH DEGENER, a resident of 26 Hollmannstrasse, Berlin, German Empire, manager, having invented 5 certain new and useful Improvements in or relating to Line Setting and Casting Machines, do hereby declare that the following is an exact specification of the same.

In the U. States Patent No. 977,280 a 10 water-cooling-apparatus for line-casting machines of the Mergenthaler system is described in which the bolt or pin of the mold-wheel or casting-wheel is divided transversely to the axis and is provided with 15 central and lateral longitudinal perforations through which the water flows, proceeding in by one perforation and out by the other, the lateral perforation finishing in an angular conduit between the two parts 20 of the bolt.

The object of the present invention is an improvement in or modification of that mentioned prior application and insures a better joint.

25 A further improvement of the prior application consists in that tubes which serve for guiding the water are arranged below the face of the mold wheel so, that no parts project beyond the faces of the mold wheel.

30 A construction according to this invention is illustrated by way of example in the accompanying drawing in which:

Figure 1 is an inner view of the mold wheel, Fig. 2 shows the mold wheel, the mold 35 wheel spindle and the bearing of the same in section, and Fig. 3 is a bottom view of the rear portion of the mold wheel spindle, Fig. 4 shows an other construction according to my invention of the rear portion of the 40 mold wheel spindle two lateral perforations being arranged, Fig. 5 shows an arrangement with an annular recess in the conical surface of the pin and Fig. 6 with recesses in both parts.

45 In the same way as in the prior Letters Patent the casting or mold wheel *a* is mounted on the spindle *b*, which rotates in the bush *d* fastened in the bearing *c*. In order to insure a better joint between the rotating 50 spindle *b* and the closing part *e*, the joint between the two parts is formed by conical

surfaces. Therefore according to this invention the spindle *b* has a conical recess at the back in which fits the conical closing part *e* provided with two conical joint surfaces *x*, *x*, between which is arranged a recess *y*, into which opens the lateral perforation *m* of the spindle *b*. The closing part *e* is also provided with two perforations, one of which opens into the point of the cone, and the second one into the recess already referred to, between the two joint surfaces. The other end of the two perforations passes into a projection *s* of the closing part, as more clearly shown in Fig. 65 3. The closing part *e* is prevented from rotating in the bearing by the projection *s* and is pressed against the conical seat by a spring *f* held by the cover *g*.

Water flows through the central perforation of the closing part to the central perforation of the spindle *b* thence to the casting mold in order to cool it, then into the lateral perforation of the spindle *b* and back to the recess between the two conical 75 surfaces of the closing part *e*, then through the lateral perforation of the closing part and away again through the perforation of the projection *s*. Of course the water could also flow in the reverse direction.

80 Of course instead of providing a central and a lateral perforation it is also possible to arrange two lateral perforations *m* and *m'* as shown in Fig. 4 of the drawings opening into two annular recesses formed between the conical joint surfaces. Also the annular recesses *y'* may be formed in the conical surface of the pin (Fig. 5) instead of the surface of the closing part, or in both of these parts, as at *y''* in Fig. 6. 90

95 For guiding the water the mold wheel itself is provided with two radial perforations *t* continuing within the casting wheel spindle and opening in the two perforations of it. For guiding the water the rim around the lateral face of the casting wheel is provided with a perforation or groove *u* joining by two holes *v* running parallel with the axis of the wheel with the radial perforations *t*. In the said perforations or 100 grooves *t*, *u* and *v* circulation-tubes are laid so, that no parts project beyond the faces

of the mold wheel. After the tube has been inserted in the said groove, the latter may be filled in with some suitable soldering material, such as tin or the like, whereby the 5 tube is held in proper position and a substantially integral structure is secured. It is necessary to employ tubes for guiding the water as the casting wheel is made of porous material so that if no tubes were laid the 10 water would leak through the pores of the mold wheel.

Having now particularly described and ascertained the nature of my invention and in what manner the same is to be performed, 15 I declare that what I claim is:

1. In a line setting and casting machine in combination a rotating pin, a mold wheel being provided with a water duct and secured to the rotating pin, said pin having 20 two perforations and being provided with a closing part having also two perforations, the adjoining surfaces of the closing part and of the pin having annular recesses, in which the perforations open and means for 25 pressing the pin and the closing part against each other, the adjoining surfaces of the pin and the closing part being of conical shape.

2. In a line setting and casting machine 30 in combination a rotating pin, a mold wheel being provided with a water duct and secured to the rotating pin, said pin having two perforations and a conical recess and being provided with a closing part having 35 also two perforations and a conical joint surface fitting into the said conical recess the adjoining conical surfaces having annular recesses into which the said perforations open and means for pressing the pin 40 and the closing part against each other.

3. In a line setting and casting machine in combination a rotating pin, a mold wheel being provided with a water duct and secured to the rotating pin, said pin having 45 two perforations and a conical recess and being provided with a closing part, having conical joint surfaces fitting into the said conical recess and leaving between them intervals into which the said perforations 50 open, said closing part also being provided with perforations opening into said intervals and means for pressing the pin and the closing part against each other.

4. In a line setting and casting machine 55 in combination a rotating pin, a mold wheel being provided with a water duct and secured to the rotating pin, said pin having perforations and a conical recess and being provided with a closing part having conical 60 joint surfaces fitting into the said conical recess, said closing part also being provided with corresponding perforations, the adjoining surfaces of the pin and the closing part being provided with an annular circuit, 65 into which one of the perforations opens

and means for pressing the pin and the closing part against each other.

5. In a line setting and casting machine in combination a rotating pin, a mold wheel being provided with a water duct and secured to the rotating pin, said pin having two perforations and a conical recess and being provided with a closing part, having a conical joint surface fitting into the said conical recess and a recess into which one 75 of said perforations open, said closing part also being provided with corresponding and communicating perforations and means for pressing the pin and the closing part against each other, the perforations in the closing 80 part being arranged so that their outer ends open in a direction at right angles to the axis of the pin.

6. In a line setting and casting machine in combination a rotating pin, a mold wheel, 85 secured to the rotating pin and being provided with two radial perforations, a groove in the rim and holes running parallel with the axis of the wheel and joining the radial perforations with the groove in the rim and a water duct through the said perforations, groove and holes of the mold wheel.

7. In a line setting and casting machine in combination a rotating pin, a mold wheel, secured to the rotating pin and being provided with two radial perforations, a groove 95 in the rim and holes running parallel with the axis of the wheel and joining the radial perforations with the groove in the rim and a water duct consisting of tubes arranged in 100 the said perforations, groove and holes of the mold wheel.

8. In a line setting and casting machine in combination a rotating pin, a mold wheel, secured to the rotating pin and being provided with two radial perforations, a groove in the rim and holes running parallel with the axis of the wheel and joining the radial perforations with the groove in the rim and a water duct consisting of tubes arranged in 110 the said perforations, groove and holes of the mold wheel, the groove in the rim of the mold wheel above the tube being filled with a suitable soldering material, substantially 115 as described.

9. In a line setting and casting machine, the combination of a rotatable mold wheel provided with a continuous pipe system for a circulating cooling medium, with a stationary member having suitable openings 120 which continuously connect with said system and supply the cooling medium thereto, the said member being arranged to project and fit into a correspondingly shaped opening in the mold wheel, in order to form 125 a close joint connection therewith.

10. In a line setting and casting machine, the combination of a rotatable mold wheel provided with a continuous pipe system for a circulating cooling medium, with a sta- 130

tionary member having suitable openings which continuously connect with said system and supply the cooling medium thereto, the said member being conically formed and 5 projecting and fitting into a corresponding conical opening in the mold wheel in order to effect a close joint connection therewith.

In witness whereof I have hereunder set my hand in presence of two witnesses.

HEINRICH DEGENER.
